UNIVERSAL CLOCK

Leo Y. Booharin, San Francisco, Calif.

Application August 5, 1939, Serial No. 288,625

2 Claims. (Cl. 58—43)

My invention relates to universal clocks.

The purpose of this invention is to provide a universal clock which is designed to indicate local time for every part of the earth at any moment.

Another purpose of this invention is to provide a universal clock which indicates local time for every part of the earth by means of time meridians covering a graphic representation of the earth's surface, such as a map.

Another purpose of this invention is to provide a device of the type described which is simple in construction, inexpensive, and efficient for the purpose intended.

In the drawing:

Fig. 1 is a front elevation of the device.

Fig. 2 is a vertical cross-section taken on the line 2—2 of Fig. 1.

Fig. 3 is a vertical section taken on the line 3—3 of the Fig. 2, showing the gear arrangement.

In general, my device consists of a graphic representation of the earth's surface, such as a map, upon which a number, preferably twenty-four, of time meridians is drawn, each representing an hour. Between each pair of said meridians additional meridians may be drawn representing fractions of an hour. An indicator is provided to give certain time value to each of the meridians which time value gradually changes, so that by means of said indicator and time meridians the local time of any part of the world may be easily determined at any moment.

In the preferred form, my device consists of a map 5 of the earth's surface with time meridians 7, drawn on a front wall 8 of my device. There are twenty-four time meridians shown on the map corresponding to twenty-four hours during which the earth makes one revolution around its axis, but, as has been stated, additional time meridians may be drawn between the meridians 7 to indicate the fractions of an hour. The meridians terminate at an arm 10 drawn on said front wall 8. Within said arm 10 there is a half circle 11 drawn on said wall 8, which is divided into twenty-four equal parts, each corresponding to an hour, and each of which is connected with the corresponding meridian by a connecting line 12. In this way every meridian is tied up to a certain division. If certain time value is given to any meridian, for instance let the central meridian 14 represent 12 o'clock noon, then the value of the rest of the meridians can be easily determined. But as the time goes by, the time value of the meridians

changes. Therefore, the means are provided for gradual change of the time value of each meridian. Said means consists of a standard time clock mechanism 15, electrically or mechanically operated, and having an ordinary hour shaft 16 extending therefrom and terminating with an hour hand 17. Within the shaft 16 there is a minute shaft 18 which extends beyond said shaft 16 and terminates with a minute hand 19. A usual knob 20 is provided for manual setting of time.

In addition to above described standard clock mechanism I provide a small gear 25 affixed to the hour shaft 16 and an idle gear 26 freely rotating about a stub shaft 27 affixed to the mechanism 15, said idle gear being in constant mesh with the gear 25. The gear 26 meshes with an internally cut gear 30, which freely rotates about the hour shaft 16. The gears 25 and 30 are so selected that the latter rotates four times slower than the former. Furthermore, the gear 30 rotates in direction opposite to that of the gear 25.

The gear 30 carries an indicator 31 in form of a disk, the upper half of which fits within the half circle 11. The indicator is preferably made of light material, such as Celluloid, or plastics, and has a collar 32 which snugly fits the outer rim 33 of said gear 30 so that ordinarily it will rotate with the latter, but may be easily rotated thereabout by an external force. The upper end of the collar 32 is preferably bent inwardly about the rim 33 in a few places, as indicated at 35 to prevent accidental displacement of the indicator 31 from said gear.

The periphery of the indicator 31 is divided into 48 divisions numbered by two rows of figures shown in close proximity to each other. The first row runs from 1 to 12 inclusively four times, and the second row runs from 1 to 24 two times. The first row indicates in usual way the time in hours, but as the first row alone cannot indicate whether the time is a. m. or p. m., a second row of figures is provided, by means of which it is made possible to determine at a glance whether the time referred to a certain meridian is a. m. or p. m. As shown in the Fig. 1 all meridians east of the meridian running through the center of the drawing indicate p. m. time.

In order to bring the indicator 31 into proper relation with the meridians, I provide a plunger 40, which is preferably made of rubber, and which is disposed in close proximity to the collar 32. The plunger 40 is carried by a shaft 41 slidable in two parallel walls 42 and 43 which are con-

nected with the clock mechanism 15. The shaft 41 terminates with a knob 45 by means of which said shaft may be pushed inwardly against the resistance of a small spring 46 urging said shaft outwardly. By pushing the knob 45 to the clock mechanism 15 the plunger 40 is brought into frictional engagement with the collar 32, and by rotating said knob the collar 32 with indicator 31 will be rotated around the gear 30 and thereby brought in desired position.

In front of the indicator 31 and in close proximity therewith I dispose a clock dial 50 which is semi-circular in the middle and has broad shoulders 51 on each side covering the lower half of the indicator 31. The clock hands, dial, and indicator are preferably covered with a glass cover 53.

The operation of the device is as follows. The correct time is set on the clock by moving the minute and the hour hands in usual manner, as for example at 10 o'clock. Then the operator locates the place of his abode on the map, let it be for example San Francisco, California, and notices which meridian runs through said place or in close proximity thereto, which in our case will be the meridian denoted by the numeral 55. Then the operator, by means of the knob 45, rotates the indicator 31 until the division marked 10 shall coincide with the line 12 connected with the meridian 55, as shown in Fig. 1. If the time is 10 o'clock p. m., then the indicator should be rotated in a manner disclosed in counterclockwise direction until said connecting line shall coincide with the division marked 10 and 22. If the place of abode is located on the map between two meridians, the indicator must be so set that the divisions thereof indicating the correct local time is set in the same relation between the two adjoining lines 12 connected with said meridians, as said place of abode is in relation to the meridians.

When the indicator 31 is correctly set, local time for any place can be easily found. The place, the local time of which it is desired to find, is first located on the map and then the corresponding meridian crossing it, or passing near by is traced down to the indicator 31 to determine what particular time corresponds to said meridian. For instance Fig. 1 shows that when it is 10 o'clock a. m. in San Francisco, it is 6 o'clock p. m. in England and 3 o'clock a. m. in Japan.

The indicator 31 rotates four times slower than the hour hand of the clock, as it has been explained heretofore, but, as the periphery of the indicator 31 is divided into forty-eight divisions, each division represents an hour. The indicator moves in counterclockwise direction, with the sun, gradually changing the time value of the meridians, but the time relation between various parts of the earth remains unchanged.

10 It shall be within the scope of this invention to provide twenty-four divisions on the indicator 31, instead of forty-eight as shown in the drawing, in which case the meridians shall be equally spaced around the whole periphery of the indicator, and the latter must rotate only two times slower than the hour hand of the clock.

Having thus described my invention, I claim:

1. A universal clock comprising a map of the earth's surface; time meridians drawn thereupon; a clock mechanism having usual hour and minute hands rotated by the corresponding hour and minute shafts, said clock mechanism being located below said map; a gear carried by the hour shaft; an idle gear meshing with the first mentioned gear; an internally cut gear adapted to mesh with the idle gear and to rotate around the hour shaft; a circular indicator carried by said internally cut gear; means for adjusting the position of the indicator in relation to the internally cut gear; a half-circle drawn on the map and circumscribing a half of said indicator, said half-circle being divided into a number of divisions equal to the number of the time meridians; and connecting lines connecting the points of division of said half-circle with the meridians.

2. A universal clock comprising a map of the earth's surface; time meridians drawn thereupon; a clock mechanism having usual hour and minute hands rotated by the corresponding hour and minute shafts; a gear carried by the hour shaft; an idle gear meshing with the first mentioned gear; a third gear meshing with the idle gear and rotating around the hour shaft in the direction opposite to that of the said shaft; a circular indicator carried by said third gear; a half-circle drawn on the map co-centrically with said indicator and divided into a number of divisions equal to the number of the time meridians; and connecting lines connecting the points of division of said half-circle with the meridians.

LEO Y. BOOHARIN.
